CHARLES MORSE, OF BOSTON, MASSACHUSETTS, ASSIGNOR, BY MESNE ASSIGNMENTS,
TO GENERAL ELECTRIC COMPANY, A CORPORATION OF NEW YORK

BUILDING STAND

Application filed August 21, 1930. Serial No. 476,927.

This invention relates to building stands such as are used to position the micas and foils during assembly of a capacitor stack and has for its object to lower the labor cost of 5 stack production. Another object is to do away with the necessity for maintaining many such building stands in stock, thereby reducing tool costs.

Heretofore it has been customary to make 10 the required number of building stands for each size stack needed. Frequently orders are received which require stacks of a different size from those for which stands have already been made up and the tool cost for such special 15 jobs has been high, owing to necessity of making up stack building stands for each size stack required.

According to this invention these costs are reduced by making it possible to use the 20 same stands for different sizes of stacks without the necessity of using measuring instruments and the like to test the adjusted position of the stand for a particular size stack desired. The labor ordinarily used in stack 25 assembly is not generally sufficiently skilled to use measuring instruments so that adjustments could not be conveniently made which would require the use of any such precision measuring instruments.

30 Referring to the drawings:

Fig. 1 is a perspective of one embodiment to this invention.

Fig. 2 shows one of the supporting members and locking plate of Fig. 1 ready for 35 engagement with the foundation member.

Fig. 3 is a top plan view of the device adjusted for one size stack.

Fig. 4 is a side elevation of the device, of 40 Fig. 3.

The building stand of this invention is intended to take the place of the prior art non-adjustable stands of the type like that shown, for example, in Figs. 1 and 2 of Pickard 45, 1,706,816, March 26, 1929.

Each stand includes a graduated or gauged foundation member 10 which may be supported on a work bench or other support by the legs shown which may rest on the bottom of the inside of the waxing tray. On foundation member 10 are two stack-supporting

members 11 and 12, one of which, 12, in the embodiment illustrated, at right, is made adjustable to vary its separation from the other stack-supporting member 12 which is secured rigidly to base 10.

On members 11 and 12 are mounted respectively up-standing guide-posts 13 and 14 cut away interiorly as shown in Fig. 3 to permit positioning of the micas or other dielectric sheets in the manner shown; these posts being cut flat exteriorly as shown to permit positioning of edges of the foils 22 so as to enable the superposed foils to be properly located within the stack of micas and foils. The foundation member 10 has transverse 55 oppositely arranged slots 15 along its longitudinal edges, Figs. 1 and 3. A plate 16 is shaped, Fig. 2, to fit into opposite slots 15 to locate the adjustable member 12 in its desired adjusted position longitudinally of base 10. Said plate 16 is secured to the member 12 by means of the screws 17 or in any other convenient manner. A longitudinal slot 18 in the foundation member 10 receives a vertical screw-headed bolt 19 extending down 60 through the two members 10 and 12. A wing nut 20 on the bolt 19 and below base 10 clamps the member 12 in its adjusted position to base 10. Plate 16 is of inverted U-shape, its 65 midportion resting on base 10 and its free leg-portions engaging in slots 15. Said leg-portions have a thickness which causes them to fit snugly in slots 15.

In Fig. 4 the micas are indicated by the numeral 21, while the foils are designated by 85 the numeral 22 but it will be understood that the thickness of both the micas and foils is considerably magnified over the actual thickness commonly used.

Some of the principal standard sizes for 90 mica sections employed today include the following, in inches: 1 x 1 $\frac{1}{4}$, 1 x 1 $\frac{1}{2}$, 1 $\frac{1}{8}$ x 2, 2 x 1 $\frac{1}{2}$, 2 x 2, 1 $\frac{3}{4}$ x 2 $\frac{1}{4}$, 2 x 3 $\frac{1}{8}$.

With the present invention it is no longer necessary to delay erection of stacks involving some unusual size stack while the building stands are being built or even to change stands in front of the operatives; and it is no longer necessary to maintain the previous investment in a large number of building 95 100

stands for each size mica, since the present invention is adapted for a wide variety of mica sizes, the slots 15 being as close together as may be desired.

To change the adjustment of the stand, making it adapted for another size, the wing nut 20 is loosened and the adjustable stack-supporting member 12 is raised from the foundation member 10 so that the locking member 16 is moved out of the slots 15 while clamping bolt 19 remains in slot 18. The member 12 with its plate 16 then is moved left or right along base 10 until the legs of plate 16 are above the proper pair of slots 15, when 12 and 16 are lowered so that the U-legs enter the slots and nut 20 is screwed up to clamp parts 10 and 12 together between said nut and the screw-head of bolt 19.

If desired, a sample stack or mica sheet of the size for which the stand is to be adjusted, may be placed between the cut-out portions of guides or posts 13, 14 as a gage for the adjusted positions of member 12 and plate 16. In this way no measuring tools other than the mica itself as a gage will be necessary in order to know that the stand is adapted for a given size stack or a given size mica. As shown in Figs. 3 and 4, in building up the stack, when the first mica sheet 21 is placed on the two stack-supporting members 11, 12, said sheet bridges over the space between members 11 and 12 and over base 10, and so with the superposed foils and micas. The widths of members 11, 12, and the locations thereon of posts 13, 14, and the locations of slots 15 in base 10, are such, however, that micas of shortest linear dimension may be used when supports 13, 14 abut against one another, i. e., when there is no space between them bridged by the elements of the stack under construction. As first above indicated, the base-member slots 15, aside from their preferred construction involving interlocking with the movable stack-supporting member 12, constitute gages or graduations indicating the desired positions of member 12 independently of the use of a sample stack or mica sheet placed as a gage between posts 13-14. When, as preferred, the interlocking slots 15 are employed, they interlock member 12 from movement along base member 10 away from the other stack-supporting member 11, and bolt 19 etc. clamp member 12 in its interlocked position from movement away from base-member 10.

What is claimed is:

1. A capacitor stack-building stand comprising a foundation member, at least two stack-supporting members, each provided with a positioning guide for the dielectrics and armatures during stack assembly; and mechanism for adjusting the separation of said stack-supporting members which includes means for interlocking the members in

adjusted position, and means for clamping the members in their interlocked positions.

2. A capacitor stack-building stand comprising a foundation member, at least two stack-supporting members, each provided with a positioning guide for the dielectrics and armatures during stack assembly; and mechanism for adjusting the separation of said members which includes means for clamping the members in adjusted position, and means enabling said members to be clamped only in certain positions and nowhere else. 70

3. A capacitor stack-building stand comprising a foundation member, at least two stack-supporting members, each provided with a positioning guide for the dielectrics and armatures during stack assembly, one of said supporting members being provided with a locking plate, said foundation member being shaped for registry with said plate at predetermined positions and nowhere else, and means for holding said supporting member with its locking plate in registry with said foundation member. 80

4. A capacitor stack-building stand comprising a foundation member, at least two stack-supporting members, each provided with a positioning guide for the dielectrics and armatures during stack assembly, said foundation member being slotted transversely a locking plate on one of said supporting members and shaped for fitting engagement with at least one slot in said foundation member; and a clamping bolt for holding said supporting member in its adjusted position on said foundation member. 90

5. A capacitor stack-building stand comprising a slotted foundation member, at least two stack-supporting members, each provided with a positioning guide for the dielectrics and armatures during stack assembly, one of said stack-supporting members being provided with a portion projecting the respective slots in the foundation member; and a clamping bolt; said foundation member being also slotted longitudinally to receive said clamping bolt. 100

6. A capacitor construction device which includes a base-member, two stack-supporting members carried thereby, and guide-posts carried respectively by said stack-supporting members, one of said stack-supporting-members being movable toward the other along the base-member to adjust the operating distances between the guide-posts; the base-member being formed with a plurality of slots in its opposite edges in succession in the direction of mobility of said movable stack-supporting member; a plate secured to said movable stack-supporting member and formed with two portions engaging in a pair of individuals of said slots in the opposite edges of the base-member; said base-member being formed also with a slot in the direc- 110 120 125 130

tion of mobility of said movable stack-supporting member; and a clamping bolt extending thru said slot and thru said movable stack-supporting member.

5 7. A capacitor construction device which includes a base-member, two stack-supporting members carried thereby, and guide-posts carried respectively by said stack-supporting members; one of said stack-supporting members being movable toward and away from the other along the base-member and the base-member and said movable stack-supporting members being provided with mutually inter-engaging portions which as 10 to the base-member are pluralized in the direction of mobility of said stack-supporting member constituting means for locating the guide-posts at different desired distances from one another; the base member being 15 formed with a slot extending in the direction of mobility of the movable stack-supporting member; and a clamping bolt extending thru said slot and the movable stack-supporting member.

20 8. A capacitor construction device which includes a base-member, two stack-supporting members carried thereby, and guide-posts carried respectively by said stack-supporting members; one of said stack-supporting members being movable toward and away from the other along the base-member, and the base-member and said movable stack-supporting members being provided with mutually inter-engaging portions which as to 25 the base-member are pluralized in the direction of mobility of the stack-supporting member constituting means for locating the guide-posts at different desired operating distances from one another.

30 9. A capacitor construction device which includes a base-member, two stack-supporting members carried thereby, and guide-posts carried respectively by said stack-supporting members, one of said stack-supporting members being movable toward and away from the other along the base-member to adjust the operating distances between the guide-posts; interlocking means holding said movable member in its adjusted positions from movement along the base-member away from the other stack-supporting member; and clamping means holding said movable member in its interlocked position from movement away from the base-member.

35 10. A capacitor construction device which includes a base-member, two stack-supporting members carried thereby, and guide-posts carried respectively by said stack-supporting members, one of said stack-supporting members being movable toward and away from the other along the base-member to adjust the operating distances between the guide-posts; the base-member being formed with a plurality of slots in its opposite edges in succession in the direction of mobility of said mov-

able stack-supporting member; and said movable stack-supporting member being formed with two projections engaging in a pair of individuals of said slots in the opposite edges of the base member.

70 In testimony whereof I hereunto affix my signature.

CHARLES MORSE.
